UNITED STATES PATENT OFFICE

GUSTAV ZECHER AND JOHANNES BRUIJNES, OF EINDHOVEN, NETHERLANDS, ASSIGNEES, BY MESNE ASSIGNMENTS, TO GENERAL ELECTRIC COMPANY, A CORPORATION OF NEW YORK

ELECTRODE IN DISCHARGE TUBES

Application filed January 6, 1926, Serial No. 79,590, and in the Netherlands March 28, 1925.

It is known to use magnesium in gasfilled discharge tubes as well as in vacuum tubes for the absorption of ingredients injurious to the discharge whilst the use of magnesium as a material for constituting the electrodes, materially decreases the starting voltage of the tube. It has therefore been proposed already to constitute one or more of the electrodes in discharge tubes, at least partly, of magnesium. Such electrodes, however, have several disadvantages. Thus, for example, the life of these electrodes is very short because they soon disintegrate if the current density at the surface of the electrodes is not kept very small. Besides, in gasfilled discharge tubes the disintegrating magnesium absorbs not only the injurious ingredients but also the gaseous filling itself, so that the pressure of the gas gradually decreases.

Now the invention has for its object the manufacture of magnesium electrodes which do not have the said disadvantages and it can more particularly be applied to gasfilled tubes in which the glowing effect is produced by the positive column.

According to the invention the discharge tube comprises one or more bodies which substantially consist of magnesium and which during or after the exhaustion of the tube are heated to such an extent that the magnesium volatilizes or disintegrates and deposits on the wall of the tube in the neighbourhood of one or more conductors serving to lead the current through the wall of the tube and in conductive connection with the said conductors.

The body may be heated in different ways. Thus, for example, a magnesium helix may be provided which at its ends is connected to two leading-in conductors and which volatilizes when galvanically heated. In this case, however, there is the disadvantage that after part of the magnesium has been volatilized, the helix breaks whilst the deposit on the wall is still insufficient. Also the magnesium may be disintegrated by initiating a discharge between two magnesium bodies connected in the tube as electrodes. This method, however, also entails various disadvantages. During the discharge, the magnesium

bodies disintegrate or volatilize and a layer of magnesium is deposited on the wall of the tube. The disadvantage of this method is that during the forming, the layer contributes already to the discharge so that in 55 the thinner places the layer on the wall of the tube is galvanically heated and volatilizes. It is therefore advisable to heat the magnesium bodies by a high frequency magnetic field, which heating permits to volatilize a sufficient quantity of magnesium and to concentrate the deposition on the wall to a good conducting layer in the immediate vicinity of one or more leading-in conductors.

Applicant has noticed that on applying a 65 magnesium layer to the wall (especially if said layer is comparatively thin), the contact of this layer with the leading-in conductor often leaves much to be desired.

It is therefore advisable to coat the leading- 70 in conductor and the wall portions lying in its neighbourhood, prior to the exhaustion of the tube with a conductive layer owing to which a safe contact with a magnesium deposited on the wall is ensured. For constituting the conductive layer graphite 75 should preferably be used which may be applied as an emulsion in water or in some binding agent for example aniline. During the exhaustion of the tube part of the ingredients injurious to the discharge and introduced into the tube together with the binders, are pumped away, which is favourably influenced by heating the wall of the tube and the graphite layer applied 80 thereto. However, any injurious ingredients which might not be removed by this heating and exhausting operation, are covered and partly absorbed by the magnesium layer applied to the graphite layer so that in the tube 85 they cannot exercise any detrimental influence.

The magnesium body should preferably be fixed on a rod of any material susceptible of being readily deprived of occluded gases, 95 such for example as iron, said rod being secured to a leading-in conductor. During the volatilization of the magnesium this rod is then already sufficiently deprived of occluded gases. Besides, with regard to the current 100

intensity required, the layer deposited on the wall may be chosen such that during the operation of the tube the rod does not contribute to the discharge and consequently neither is heated to a high temperature.

The discharge tube comprising one or more electrodes constituted in accordance with the process of the invention, offers the advantage that it has a long life since owing to the large surface of the electrode the temperature of the latter is not raised very much so that the material deposited on the wall disintegrates or volatilizes only in a slight measure. Besides, any ingredients injurious to the discharge and present in the tube, are absorbed while the layer acting as an electrode is being applied and during the operation of the tube and the operating voltage and the starting voltage of the tube are materially smaller than is the case with the usual electrodes. In a mode of realization of the invention the wall of the tube in the neighbourhood of the leading-in conductors is given such a shape that the magnesium which has deposited on the wall and which disintegrates or volatilizes during the operation of the tube, substantially deposits again on the wall portion coated already with magnesium. Owing to this the volatilization of magnesium which with the electrodes according to the invention is already small, does not exercise any detrimental influence on the life of the tube as the layer once produced remains intact. For this purpose the wall of the tube in the neighbourhood of the leading-in conductors should preferably be made substantially spherical. Besides, in order to prevent any deposition of magnesium on the wall portions which do not act as an electrode, the tube near the portion acting as an electrode, may be kinked.

The invention will be more clearly understood by referring to the accompanying drawing in which

Figure 1 represents a discharge tube in which the glowing effect is produced by the positive column, said tube comprising electrodes constituted in accordance with the process of the invention and

Figure 2 shows a detail of one of the electrodes in such a tube.

In the drawing the numeral 1 refers to a glass tube which at both sides is kinked and which is provided with spherical ends 2. In each end 2 is sealed a leading-in wire 3, for example, of platinum or of any other material allowing of being readily sealed in glass and having a coefficient of expansion slightly different from that of glass. To the leading-in wire is fixed, for example by welding, a U-shaped rod 4 of iron on which a magnesium helix 5 is provided. A mica screen 6 may be fixed to the rod 4 in order to limit the deposition of magnesium as much as possible to the wall of the sphere 2.

Before the end 2 is sealed in the tube 1, a portion of the leading-in wire 3 as well as the glass wall in the nearest proximity of this wire is coated with a layer 7 of conductive material. Preferably an emulsion of graphite in water should be used for this purpose. The ends 2 are then sealed to the tube 1, whereupon the tube is exhausted in the known manner and is provided with a gaseous filling for which purpose frequently neon under a pressure of some millimetres of mercury is used.

During or after the exhaustion operation a coil (not shewn in the drawing) is arranged around each end 2, in which coil a high frequency magnetic field of such intensity is excited that the magnesium helix 5 volatilizes and on the wall of the tube a magnesium layer 8 is formed which also covers the conductive layer 7.

After the magnesium helix 5 has substantially been volatilized and the tube has been closed by fusion, the discharge tube is ready for use and may be connected to some source of potential which in the drawing is diagrammatically represented by a secondary winding 9 of a transformer.

Owing to the large surface of the electrode the latter is not heated during the operation of the tube to a high temperature so that the magnesium layer only slightly volatilizes. Besides, the end 2 of the tube has such a shape that any disintegrating or volatilizing magnesium particles substantially strike on portions of the tube which are already coated with magnesium.

What we claim is:—

1. A discharge tube with positive column discharge and a leading-in conductor in the neighbourhood of which a portion of the wall of the tube is coated with a conductive layer which is at least partly covered by a magnesium coating, this coating serving as an electrode.

2. A discharge tube with positive column discharge and a leading-in conductor in the neighbourhood of which a portion of the wall of the tube is coated with a graphite layer, which is at least partly covered by a magnesium coating, this coating serving as an electrode.

3. A discharge tube with positive column discharge and an electrode consisting of a wall covering of magnesium, the wall of the tube in the neighbourhood of the electrode being substantially spherical, so that the magnesium which has deposited on the wall and which volatilizes during the operation of the tube substantially deposits again on the spherical part of the wall of the tube.

4. A discharge tube with positive column discharge and a leading-in conductor in the neighbourhood of which a portion of the wall of the tube is coated with a conductive layer which at least partly is covered by a magne-

sium coating serving as an electrode, the wall of the tube in the neighbourhood of the electrode being substantially spherical so that the magnesium which has deposited on the 5 wall and which volatilizes during the operation of the tube substantially deposits again on the spherical part of the wall of the tube.

5. A discharge tube with positive column discharge and a leading-in conductor in the 10 neighbourhood of which a portion of the wall of the tube is coated with a graphite layer, which at least partly, is covered by a magnesium coating serving as an electrode, the wall of the tube in the neighbourhood of the electrode 15 being substantially spherical so that the magnesium which has deposited on the wall and which volatilizes during the operation of the tube substantially deposits again on the spherical part of the wall of the tube.

20 6. In the manufacture of gas-filled discharge tubes for positive column discharge, the process of making an electrode which consists in coating the inner wall of the tube adjacent the leading-in conductor with a conductive layer and then heating a body 25 consisting substantially of magnesium adjacent said layer to volatilize and deposit the magnesium thereon.

7. In the manufacture of gas-filled discharge tubes for positive column discharge, 30 the process of making an electrode which consists in coating the inner wall of the tube adjacent the leading-in conductor with a graphite emulsion and then heating a body 35 consisting substantially of magnesium adjacent said graphite layer to volatilize and deposit the magnesium thereon in contact with the leading-in conductor.

8. A positive column discharge device comprising an envelope having a tubular portion 40 with electrode chambers of greater diameter than said tubular portion at each end thereof, a lead-in member sealed into each electrode chamber and a metallic coating covering the inner wall of each electrode chamber, 45 contacting with its respective lead-in member, and bounded by the junction of the electrode chamber and tubular portion.

In testimony whereof we affix our signatures at the city of Eindhoven this 7th day 50 of December, A.D. 1925.

GUSTAV ZECHER.
JOHANNES BRUIJNES.
